UNITED STATES PATENT OFFICE

2,518,551

CLASP FOR WRIST WATCH BANDS

Richard Jaccarino, Westchester County, N. Y.

Application March 30, 1948, Serial No. 17,982

2 Claims. (Cl. 24—71)

1

My invention relates to clasps for wrist watch bands, and the object of the invention is to provide a clasp that will automatically compensate for normal changes in fullness of the wearer's wrist.

Another object of the invention is to provide a clasp having a yieldingly attached slide provided with a predetermined longitudinal displacement.

A further object of the invention is to provide a clasp of the folding type, having a manually releasable latch which automatically locks the clasp in the folded or closed position.

In the appended drawing forming part of this application:

Figure 1 is a longitudinal section through the clasp in an unfolded or open position;

Figure 2 is a fragmentary elevation of the hinged sections of the clasp as shown in Figure 1;

Figure 3 is a cross-section on line 3—3, Figure 1, through the clasp in a closed or locked position;

Figure 4 is a cross-section on line 4—4 of Figure 1;

Figure 5 is a cross-section on line 5—5, Figure 1, when the clasp is in locked position; and

Figure 6 is a cross-section on line 6—6, Figure 1.

Referring to the drawing:

10 is a housing of the clasp, which is shallow in depth and is slightly arcuated to conform to the curvature of the wrist. It is open at each end and also in the back through its entire length, but not through its entire width, therefore leaving at each side wall 12 strip-like portions 11, as shown best in Figures 3 to 6 inclusive.

The side walls 12 of the housing 10 with the strips 11 on one side and the top 13 on the other side form a U-channel at each side of the housing 10, as seen from Figures 3 to 6 inclusive. The housing 10 near one end thereof has lugs 14, each rising from a corresponding strip 11 towards the top. The lugs 14 on the opposite strips 11 are aligned and are clear of the bottom opening of the housing.

Each lug 14 is provided with an aperture constituting a bearing for the corresponding trunnions 15 of a link 16 arcuated longitudinally in conformity with that of the housing 10. The link 16 at the other end has also trunnions 17, bearing in corresponding apertures 18 provided in the side walls 19 of a cover 20 for the bottom opening of the housing 10. The cover 20 is also arcuated to conform to that of the housing, and it is provided with hooked portions 21 in the side walls near the other end thereof. A portion of

the side walls of the cover 20 is cut out as shown at 22 to permit the laterally extending edges 23 of the links 16 to fit therein (see Figure 4) when the cover 20 and the link 16 are folded into the housing. The central part of the side walls 19 of the cover 20 is raised sufficiently as shown at 24 to bear against the inner face of the top 13 of the housing 10 when the cover 20 is closed.

10 The side walls 12 of the housing near the lugs 14 have elongated facing and aligning slots 25 (see Figures 1 and 5) into which a pin 26 is fitted to move longitudinally of the housing 10. The pin 26 is provided with heads 27 on the outside of the side walls 12 of the housing 10 to prevent the pin proper from moving out axially. By gripping the heads 27 with the fingers, the pin may be moved against compression springs 28 located within the U-channels of the housing, which springs 28 have one end thereof butted against the pin 26 while the other end is engaging a brace or bar 29 extending within the housing transversely thereto, as best seen in Figures 1 and 5.

When the link 16 and the cover 20 are folded into the housing 10, the hooks 21 on the walls 19 of the cover 20 force the pin 26 to move by compressing the springs 28, thus permitting the hooked parts to register with the pin 26; the pressure on the springs 28 being released, the pin 26 is returned by the springs to engage the hooking parts 21, thereby locking the folded clasp, whereby the cover is automatically latched in the housing.

35 The clasp cannot be opened until the pin 26 has been moved by gripping with fingers the heads 27 thereof on the outside of the sides of the housing 10 and moved to compress the springs 28 to move the pin 26 to clear the hooks 21, so that the links 16 and cover 20 can be unfolded as shown in Figure 1. The cover 20 at the end remote from where it is connected with the link 16 has a cross-bar 30, to which a wrist band is securable.

45 The housing 10 at the end remote from where the movable pin 26 is located is fitted with a slide 31. The slide is preferable in the shape of a U-channel, the sides 31' of which engage the side walls 12 of the housing 10 with the bottom of slide 31, contacting the interior surface of the top 13 of the housing 10, as best shown in Figure 1. The end portions of the sides 31' of the slide which extend out at the end of the housing 10 are rounded up and carry thereat a bar 32 extending across the slide and secured in 53 the walls 31' thereof. This bar 32 serves as a

means of securing a wrist band thereto. To prevent the slide 31 from being pulled out of the housing 10, a lug 33 is formed on each wall 31' at the inner end of the slide 31, which lug 33 is made to butt against a corresponding stop 34 formed at the end of strip 11, where the slide is fitted, as best shown in Figures 1 and 6.

The slide 31 is normally maintained within the housing 10 by tension springs 35, each spring has one end thereof hooked on the corresponding lug 33 of the slide 31 and the other end of each spring 35 is anchored to the bar 29, as will be seen from Figures 1 and 3.

Thus it will be seen that the slide 31 is yieldingly attached to the housing of the clasp, and the slightest pull on the bar 32 carried by the slide will cause it to move out from the housing. In consequence any change in the fullness of the wrist would be automatically compensated by the yielding attachment of the slide with the clasp formed by the springs 35.

I claim:

1. A clasp comprising a shallow housing open at the bottom, a cover for the bottom, said cover having means at one end for attaching a wrist band, a link hinged with one end to the other end of the cover, the other end of said link being hinged near one end of the housing, whereby said link will fold into the housing when the cover closes the bottom of the housing, a slide mounted in the housing at the end remote from where the link is hinged, said slide having means for securing a wrist band thereto, means connecting yieldingly the slide to the housing for retracting the slide, a spring actuated sliding pin in the side walls of the housing near the hinge of the link with the housing, said pin extending transversely of the housing to slide longitudinally of said housing and having means on the outer

faces of the side walls for sliding the pin against the resistance of the spring, and hooking means carried by the cover to engage the sliding pin to lock the cover to the housing when closing the bottom opening.

2. A clasp comprising a longitudinally curved shallow housing provided with a longitudinal opening at the bottom so as to provide U-channelled passageways on the sides thereof, a correspondingly curved cover for said bottom, having means at one end thereof for attaching a wrist band, a correspondingly curved link connected with one end thereof to the end of the cover remote from where the band attaching means are provided, said link being hinged with the other end thereof to one end of the housing, hooking means at the band attaching means of the cover, a pin slidably mounted in the housing, to move transversely of its axis, springs in the channelled portion of the housing pushing the pin towards the hooking means when the cover is in the bottom opening, said pin having finger gripping means at each side of the housing for moving the same against the springs and whereby the clasp may be unfolded, and means for yieldingly securing a wrist band to the housing.

RICHARD JACCARINO.
